UNITED STATES PATENT OFFICE.

GODEL KALENOFF OF BROOKLYN, NEW YORK

TOOTH CLEANER.

Application filed February 18, 1928. Serial No. 255,348.

This invention relates to tooth cleaners, an object of the invention being to provide a simple, inexpensive and efficient means for supporting a thread of any suitable material such as cotton, silk, dental floss or any other material, and which will hold the thread as loosely or as taut as desired, and can be most effectually manipulated to thoroughly clean between the teeth and also clean the gums adjacent the teeth to remove any food or other particles which cannot be dislodged with the ordinary brush.

A further object is to provide a device of this character having an improved arrangement of grooved, thread-receiving posts on which the thread may be wound a number of turns and will effectually maintain itself in position without tying or any other fastening means.

With these and other objects in view, the invention consists in certain novel features of construction and combinations and arrangements of parts, which will be more fully hereinafter described and pointed out in the claim.

In the accompanying drawings—

Figure 1 is a view in elevation illustrating one form of my improved device;

Figure 2 is a view, partly in elevation and partly in section, illustrating my improved device as an attachment for a toothbrush handle;

Figure 3 is an enlarged view in elevation of one of the thread-receiving posts shown in Figure 1.

Referring more particularly to Figure 1, my improved device is composed of a single length of wire A. The extremities of the wire are bent at right angles to the main portion of the wire so as to provide a pair of posts 2 and 3, spaced apart. The intermediate portion of the wire is bent upon itself, forming a handle 4 of any desired length and shape.

One of these posts 2 is illustrated on an enlarged scale in Figure 3, from which it will be noted that the outer end of the post has an annular V-shaped groove 5 therein for the reception of a cord 6, which may be of silk, dental floss, cotton or any other desired material.

I would call particular attention to the shape of the groove 5, as this shape of groove enables me to wind a cord a certain number of turns around the same so that the cord

will wedge in the groove and which is self-sustaining without tying the same or securing the cord in any other manner.

In Figure 2 I illustrate a modification in which my improved device, indicated generally by the reference character B, constitutes an attachment for a toothbrush handle, indicated by the reference character C. The device B in this form of my invention is stamped from sheet metal and comprises spaced posts 7 and 8 having grooves 9 therein, similar in shape to the grooves 5 for the reception of the cord 6.

On one end of the device B a tongue 10 is provided and perforated to receive a pivot pin 11 secured in the toothbrush handle C, and said handle is slotted or bifurcated at one end, as indicated at 12, so as to allow the device B to be swung on the pivot 11 and enclosed or housed in the handle.

The tongue 10 is of sufficient length to project from the end of the tooth brush handle when the device B is housed in the handle, and hence this will facilitate the turning of the device to operative position.

The operation of the device is as follows:

For each use, a new length of cord is positioned on the posts and this may be as loose or as taut as desired. The operator can then force the cord between the teeth and move the device back and forth and in all directions and, in fact, can insert his finger or thumb under the cord and give to the cord any desired manipulation to most effectually clean the teeth.

Various changes and alterations might be made in the general form of the parts described without departing from my invention and hence I do not limit myself to the precise details set forth but consider myself at liberty to make such changes and alterations as fairly fall within the spirit and scope of the appended claim.

I claim:

A tooth cleaner, comprising a single integral member, spaced grooved cord-receiving posts on the member, a toothbrush having a groove therein to receive the device, a perforated tongue on the device, and a pivot pin secured in the toothbrush handle and projected through the tongue.

Signed at New York in the county of New York, and State of New York this 17th day of February, A. D. 1928.

GODEL KALENOFF.
